UNITED STATES PATENT OFFICE.

AARON P. ROBINS DRUCKER, OF COLORADO SPRINGS, COLORADO.

MEANS FOR PRODUCING PERPETUAL INVENTORIES.

Application filed January 14, 1922. Serial No. 529,244.

To all whom it may concern:

Be it known that I, AARON P. ROBINS DRUCKER, residing at Colorado Springs, county of El Paso, State of Colorado, have 5 invented certain new and useful Improvements in Means for Producing Perpetual Inventories; and I do hereby declare the following to be a full, clear, and exact description of the invention, such as will enable others skilled in the art to which it 10 appertains to make and use the same.

My invention relates to inventory systems, and its general object is to produce an inventory system which can be applied in 15 any mercantile or manufacturing establishment, no matter how varied or complex its stock, and by means of which inventories can be had at any desired time with ease and dispatch. A more particular object is to 20 produce an inventory system which can be operated to obtain inventories at regular intervals of comparatively short duration, whereby there is obtained what may properly be called a perpetual inventory. Other 25 objects and advantages of the invention will become apparent as this description proceeds.

Referring to the accompanying drawings 30 for a particular description of a system embodying my invention,

Fig. 1 illustrates sections of a catalogue used in the system.

Fig. 2 represents one of the inventory sheets used in said system.

Fig. 3 shows an inventory sheet of slightly 35 different construction.

Fig. 4 shows a form of sales ticket which may advantageously be employed in the system.

40 For carrying the invention into practice all articles of merchandise in the store where the inventory system is to be applied are classified and catalogued. For this purpose a catalogue is prepared containing a list of 45 the several departments into which the store is divided, identified by numerical or other suitable designations, and a classified list of all articles belonging in the respective departments. Fig. 1 shows sections of a catalogue of this kind for a large department store. The departments are identified by Roman numerals and the articles under the several departments are classified according to the Dewey decimal system, but it will 55 be obvious that other suitable systems of classification may as well be employed.

Thus every article of merchandise in the store has a peculiar designation indicating the department where the article is found, its class and subclass. For example, men's 60 soft hats are designated by the symbols XVIIIm, 3.1, indicating men's wearing apparel department, class headwear and subclass soft hats.

Individual to each article there is provided an inventory sheet, such as illustrated by Fig. 2. The several inventory sheets may be arranged in classified order and bound in one or more volumes, but I prefer a loose leaf system as more flexible and 65 easier to manipulate.

As illustrated, each leaf has on its upper left hand corner symbols indicating the department, class and subclass of the articles pertaining thereto, the particular articles 75 designated in the illustration being men's silk shirts. In the upper right hand corner of each sheet are printed the legends, "Maximum," "Minimum," "When to order." Opposite the legend "Maximum" is printed 80 a number representing the maximum number or amount of the particular articles which should be in stock, and opposite the legend "Minimum" is printed a number representing the minimum number or amount 85 of such articles. At the top of the sheet is a space for entering the per cent profit on the particular article. The sheet is further provided with columns for entering the total number and cost of articles purchased each 90 month of the year, similar columns for entering the total number and price of articles sold per month, and similar columns for entering the total number and cost of the articles on hand at the end of each 95 month, and a column for entering remarks pertinent to the articles pertaining to the sheet.

Formed on the lower part of the sheet are three pockets adapted to receive respectively 100 invoice slips showing the number and cost of articles received, sales slips showing the number and price of articles sold and memoranda slips relative to the particular articles.

Salesmen's pads used in my system have 105 in addition to the usual original and carbon tickets a second carbon, which is preferably formed by transverse perforations into a plurality of separable sections, each section 110 adapted to have recorded thereon articles of one class only. When articles of more than

one class are sold to a purchaser, the different classes of articles are recorded on separate sections, articles of one class only being recorded on a single section. This second carbon ticket goes to the inventory clerk, and the purpose of dividing the ticket into easily separable sections is to make it easy for him to divide the ticket into as many sections as there are classes of articles recorded thereon, thus obtaining a separate slip for each class of articles. Fig. 4. illustrates a ticket of this kind. Preferably the ticket is formed of relatively heavy paper, so as to facilitate the handling of the separate slips into which it is divided.

The operation of the system is as follows:

As goods are purchased and received, the invoice itself, if the items on it are all of the same class and subclass, is deposited in the purchase pocket of the inventory sheet individual to that class and subclass. If the items belong to different subclasses, a copy of the invoice is made on separate slips, articles of one class only being recorded on a single slip. The slips are then deposited in the purchase pockets of their respective sheets. Thus a record to date is kept, in association with each inventory sheet, of the number and cost of the respective articles received.

As heretofore mentioned, the sales tickets are in triplicate. The original goes to the customer and one carbon to the bookkeeper, as customary. The second carbon goes to the inventory clerk, who separates it into sections or slips, according to the classes of articles entered thereon, placing the slips in the sales pockets of their respective inventory sheets. If only one section of the ticket is used, the clerk detaches this section and files it in the sales pocket of its inventory sheet, throwing away the unused sections. Thus a record is kept to date, in association with each inventory sheet, of the number and price of the respective articles sold.

At the end of each month, or oftener if necessary, the inventory clerk will insert the total purchases and sales in the purchase and sales columns in the line of the respective month, these totals being obtained by adding the items on the purchase and sales slips respectively. Next he will calculate the returned sales and purchases of articles of each class and subtracting these respectively from the total sales and purchases, he obtains and enters in the balance columns the number and cost of articles on hand. If the balance is near the minimum indicated by the number in the upper right hand corner of the sheet, he will flag the sheet with a red flag to call the manager's attention to that fact. Any pertinent remarks made by a customer or salesman with regard to an article are noted on slips and deposited in the "memoranda" pocket of the sheet pertaining to

that article; and these notes are entered monthly, or oftener, in the remarks column in the line of the respective month.

Fig. 3 shows an inventory sheet of slightly different construction from that shown in Fig. 2. In the construction illustrated by Fig. 3 the purchase and sales pockets at the bottom of the sheet are each divided into a plurality of sections, or separate pockets, each pocket adapted to the size of the slips and adapted to hold a definite number of slips. The memoranda pocket consists of a number of graduated sections or pockets. Further, the top of the sheet has provision for the insertion of data showing the per cent of operating expenses apportioned to the particular article, the average per cent of profit thereon and the annual turnover of the article.

My system has many advantages, among the more obvious of which may be mentioned the following:

It gives a comprehensive statement of the movement of the goods for a year in monthly totals.

It enables the buyer to see at a glance when there is a need to replenish goods and when there is enough of an article in stock.

It gives the management a ready means for ascertaining which articles pay for themselves and which do not.

It assembles and classifies all important remarks, suggestions etc. made by the sales people or customers with regard to the various articles, whereby this data can be used to the best advantage by the management.

I have endeavored to describe a system embodying my invention, with particularity, but I do not intend thereby to limit the invention to the specific embodiments described. Many changes and modifications in the instrumentalities as well as in the method of operation will readily occur to those skilled in the art to which the invention pertains. For example, the purchase sales and memoranda slips, instead of being associated directly with the inventory sheets may be arranged separately therefrom in a card index classification, without departing from the spirit of my invention. Other changes and perhaps improvements could be made in the specific embodiment described without changing the real essentials of the system.

I claim:

1. Means for maintaining a perpetual inventory of goods grouped into classes, comprising a series of record sheets each bearing indicia denoting one class only, each sheet being provided with spaces marked for the reception of data relative to total purchases and sales of goods in said class during a certain period of time, with similar spaces marked for the reception of data relative to the amount of goods in said class

left in stock, and with spaces marked for the reception of data relative to the maximum and minimum amount of goods of said class to be kept in stock.

5. 2. Means for maintaining a perpetual inventory of goods grouped into classes, comprising, in combination with invoice slips and sales slips issued during the regular order of business, said slips indicating purchases and sales of goods, and the class thereof, a series of record sheets each bearing indicia denoting one class only, each sheet being provided with spaces marked for the reception of data relative to total purchases and sales of goods in said class during a certain period of time, said sheets also carrying pockets adapted to receive said invoice and sales slips and marked to indicate the classification of said slips.
10. 3. Means for maintaining a perpetual inventory of goods grouped into classes, comprising, in combination with invoice slips and sales slips issued during the regular order of business, said slips indicating purchases and sales of goods, and the class thereof, a series of record sheets each bearing indicia denoting one class only, each sheet being provided with spaces marked for the reception of data relative to total purchases and sales of goods in said class during a certain period of time, and with spaces marked for the reception of data relative to the maximum and minimum amount of goods in said class to be kept in stock, said sheets also carrying pockets adapted to receive said invoice and sales slips and marked to indicate the classification of said slips.

15. 4. Means for maintaining a perpetual inventory of goods grouped into classes, comprising a series of record sheets each bearing indicia denoting one class only, each sheet being provided with spaces marked for the reception of data relative to the total purchases and sales of goods in said class during a certain period of time, with similar spaces marked for data relative to the maximum and minimum amount of goods in said class to be kept in stock, with a space marked to receive data relative to the date of the next purchase of said goods, with a space marked to receive remarks relative to said goods, and pockets carried by said sheet marked for and adapted to receive purchase and sales slips covering the goods of said class.

goods to be kept in stock, and with spaces marked for the reception of data relative to the percentage of profits on the sales of goods in said class during said period.

5. Means for maintaining a perpetual inventory of goods grouped into classes, comprising a series of record sheets each bearing indicia denoting one class only, each sheet being provided with spaces marked for the reception of data relative to the total purchases and sales of goods in said class during a certain period of time, with similar spaces marked for data relative to the amount of goods in said class left in stock, with spaces marked for the reception of data relative to the maximum and minimum amount of goods to be kept in stock, with spaces marked for the reception of data relative to the percentage of profits on the sales of goods in said class during said period, and with a space marked to receive data relative to the date of the next purchase of said goods.

6. Means for maintaining a perpetual inventory of goods grouped into classes, comprising a series of record sheets each bearing indicia denoting one class only, each sheet being provided with spaces marked for the reception of data relative to the total purchases and sales of goods in said class during a certain period of time, with similar spaces marked for data relative to the amount of goods in said class left in stock, with spaces marked for the reception of data relative to the maximum and minimum amount of goods to be kept in stock, with spaces marked for the reception of data relative to the percentage of profits on the sales of goods in said class during said period, with a space marked to receive data relative to the date of the next purchase of said goods, with a space marked to receive remarks relative to said goods, and pockets carried by said sheet marked for and adapted to receive purchase and sales slips covering the goods of said class.

In testimony whereof I affix my signature.
AARON P. ROBINS DRUCKER.
